UNITED STATES PATENT OFFICE.

ALBERT HUPP, OF KANSAS CITY, MISSOURI.

MAIL-BAG STATION-CRANE.

1,020,610.

Specification of Letters Patent. Patented Mar. 19, 1912.

Application filed October 31, 1910. Serial No. 590,043.

To all whom it may concern:

Be it known that I, ALBERT HUPP, a citizen of the United States, residing at Kansas City, in the county of Jackson and State of Missouri, have invented certain new and useful Improvements in Mail-Bag Station-Cranes, of which the following is a specification.

This invention relates to mail bag station 10 cranes and has for its object the production of a device of this character which will properly support a mail bag in the path of a mail catching appliance carried by a train, can be set in operative position easily and 15 quickly, and when relieved of a mail bag by a passing train, operates without material or injurious shock or jar.

A further object is to produce a device of 20 this character embodying bag-holding jaws which swing in the same direction the train is moving as the catcher of the latter engages and withdraws the bag from the said jaws so that the transfer of the bag from the crane to the car shall be effected without 25 injury to the bag.

With these objects in view and others as 30 hereinafter appear, the invention consists in certain novel and peculiar features of construction and organization as hereinafter described and claimed; and in order that it 35 may be fully understood reference is to be had to the accompanying drawings, in which—

Figure 1, is a plan view of a pair of station cranes embodying my invention, one of them being provided with a protecting cover. Fig. 2, is a vertical section on the line II—II of Fig. 1. Fig. 3, is an enlarged vertical section on the line III—III of Fig. 40 1. Fig. 4, is a section on the line IV—IV of Fig. 2; but on a larger scale than Fig. 3. Fig. 5, is a detail perspective view of a catch for holding the bag carrying arms in operative position.

In the said drawings where like reference characters indicate corresponding parts in all the figures, 1 is a tubular standard provided with an enlarged foot piece 2, whereby the standard may be reliably secured to a 45 cross tie 3 of a trackway, not shown, the cross tie 3 being preferably an extended tie of the trackway so that the standard shall bear a fixed relation to the trackway. Mounted upon the upper end of the standard 50 is a circular head 4, provided with a stem 5 depending into the standard and se-

cured therein by a cross pin 6, and said head is provided in its upper edge with a V-shaped notch 7 and with a pair of flanking V-shaped notches 8 of large size as compared with notch 7; the function of this notched head will hereinafter appear.

9 is a sleeve fitting loosely upon the standard and susceptible of rotatable and vertical movement and journaled upon the standard 65 and also adapted for sliding movement thereon is a pair of brackets 10, provided with sockets 11 receiving the opposite ends of the sleeve 9 and secured to the latter by set screw 12. The brackets 10 are horizontally bifurcated to provide arms 13, and the shoulders 14 have centering studs 15. The upper arms 13 are provided at their upper sides with ribs 16, similar ribs being provided at the undersides of the lower arms 13, 70 and extending through said arms and ribs are bolts 17, engaged at their threaded ends by retaining nuts 18. The bolts 17 of the upper bracket are utilized to secure a vertical catch 19 upon said bracket, said catch 75 being provided with a rearwardly projecting tooth 20 overhanging the head 4 and adapted for engagement with the notch 7 or either of the notches 8. Pivoted on bolts 17 between arms 13 of the brackets 10 are 80 bell cranks consisting of outwardly projecting arms 21, forwardly projecting tubular arms 22 and stiffening ribs 23, between said arms, the arms 21 having rearwardly projecting studs 24 around which fit the front 85 ends of coiled springs 25, the rear ends of said springs fitting around studs 15, the interposition of said springs between shoulders 14 and arms 21, tending to hold arms 22 parallel with the cross tie 3 and projecting toward the trackway. The said tubular arms 22 are provided with jaws 26 which are bent in opposite directions at their free ends at 27, to form flaring mouths between them into which a mail bag, not shown, may 90 be easily and quickly slipped and out of which such bag may be readily withdrawn, and secured upon said jaws to limit and cushion their approach, is a pair of short sleeves 28 of rubber or equivalent material.

For the purpose of protecting a mail bag carried by the jaws 26 from injury by rain or snow and to exclude both from head 4, I provide the following construction; 29 is an angle bracket secured to the catch 19, in any suitable manner, and secured to the upper end of said bracket and overlying head

4, is a plate 30, a substantially similar plate or cover 31 being secured to the bracket 29, above the outer ends of the jaws 26, for the purpose of protecting the upper end of a mail bag carried by said jaws, it being understood that the mail bag is arranged vertically and while so held one end is slipped between one pair of jaws, the other end being then slipped between the other pair of jaws, and to accomplish this easily, I preferably provide a platform 32 adjacent to and at the opposite side of the crane from notch 7.

In practice there will usually be a plurality of cranes and in such event the platform will extend from the first to the last of the series of cranes and will be mounted upon angle brackets 33.

The standards are braced by inclined braces 34, which, like the standards, are preferably secured to extended cross ties so that the outer ends of the braces shall bear a fixed relation to the trackway. It will be noticed that the movable bag carrying frame 25 constituted by sleeve 9, brackets 10, and the spring actuated jaws 26, is suspended from the head of the standard by means of the catch 19, and that when the tooth of the catch is in engagement with notch 7, the 30 said jaws stand at right angles to and project toward the trackway for the purpose of holding the bag in the path of the catcher of a mail car upon the trackway. When the tooth of the catch is in engagement with either of the notches 8, the jaws extend 35 laterally and rearwardly over the platform so that a mail bag can be easily slipped between them, the resistance of the springs 25 being sufficient to clamp the bag firmly 40 and reliably in place, and the sleeves 28 serving not only to prevent the jaws from coming together when the bag is removed, but as a gage to limit the distance which the bag will be inserted between the jaws.

45 Assuming that the bag carrying frame is disposed with its jaws over the platform and that the mail bag has been inserted between the jaws, the operator rotates the frame to swing the jaws and bag toward 50 the front of the standard. In doing this he exerts sufficient force to cause the tooth of the catch to ride upwardly and forward upon the head, the bag carrying frame incidentally rising with the catch. When the 55 frame attains a position almost at right angles to the platform the tooth 20 of the catch rides down into notch 7, in which position the weight of the frame and of the bag maintains the catch until the bag is removed by a passing catcher. As this takes 60 place the catcher applies a lateral pressure on the bag and hence swings the supporting frame thereof and causes the tooth of the catch to ride up out of the notch 7, the impetus of the push applied to the frame by

the carrier through the instrumentality of the bag, causing the frame to make an extended swinging movement, additional impetus being given to the first part of this movement by the gravitational movement of the tooth down into the notch 8. The swing may be sufficient to carry the tooth up the rear wall of the notch and then down into the other notch 8, but ordinarily the jaws, through the pressure applied in the withdrawal of the bag therefrom, will eventually assume a position in vertical alinement with the first of the notches 8 encountered by the catch. By virtue of the travel of the tooth upon the inclined walls of the notches 8, there will be no sudden checking of the rotary movement of the frame when relieved of the mail bag and hence the arrest of said frame will be without material shock or jar and therefore without any possibility of injury to any part of the crane, and because the frame yields and permits the jaws to move with the catcher of the train, heavily loaded paper bags are slipped from between the jaws endwise of the same without injury.

From the above description it will be apparent that I have produced a mail bag station crane possessing the features of advantage enumerated, and while I have illustrated and described the preferred embodiment of the same I wish it to be understood that I do not desire to be restricted to the exact details of construction shown and described as obvious modifications will suggest themselves to one skilled in the art.

I claim:

1. A mail bag crane, comprising a standard, a frame arranged to turn on said standard, embodying a pair of jaws for engagement with the upper part of a mail bag and a similar pair of jaws for engagement with the lower part of the mail bag, yielding means for closing said jaws, a fixed part and a part movable with said frame and adapted to coöperate with said fixed part in holding the frame with its said jaws projecting in a predetermined direction against accidental movement; said fixed and movable parts also having a relative vertical movement during the rotatable movement of the frame.

2. A mail bag station crane, comprising a standard, a frame arranged to turn on said standard embodying a pair of jaws for engagement with the upper part of a mail bag and a similar pair of jaws for engagement with the lower part of a mail bag, yielding means for closing the jaws, a part rigid with the standard and provided with a shallow notch and a deep notch, and a catch rotatable with said frame, provided with a tooth for engagement with the shallow notch to hold the bag in operative position and for engagement with the other notch when a bag is being secured between the jaws.

3. A mail bag station crane, comprising a standard, a frame arranged to turn on said standard embodying a pair of jaws for engagement with the upper part of a mail bag and a similar pair of jaws for engagement with the lower part of a mail bag, yielding means for closing the jaws, a head rigidly secured to the upper end of the standard and provided forward of its center with a shallow notch and at opposite sides of its center with V-shaped notches, and a catch rigidly secured to the upper part of the said frame and provided with a tooth overhanging said head and adapted for engagement with the shallow notch or with either of said V-shaped notches.
4. A mail bag station crane, comprising a standard, a frame arranged to turn on said standard embodying a pair of jaws for engagement with the upper part of a mail bag and a similar pair of jaws for engagement with the lower part of a mail bag, yielding means for closing the jaws, a head rigidly secured to the upper end of the standard and provided forward of its center with a shallow notch and at opposite sides of its center with V-shaped notches, a catch rigidly secured to the upper part of the said frame and provided with a tooth overhanging said head and adapted for engagement with the shallow notch or with either of said V-shaped notches, a bracket secured to the catch, a plate secured to the bracket and overlying said head and catch, and a cover carried by said bracket and overlying the free or outer ends of said jaws when the same are closed.
5. A mail bag station crane, comprising a standard, a sleeve arranged to turn and slide thereon, a horizontally bifurcated bracket secured to each end of the sleeve, a pair of bell cranks pivoted in the bifurcation of each bracket, springs bearing at their opposite ends against the brackets and the bell cranks to hold adjacent arms of the latter together, jaws secured to said last-named arms, a part rigid with the standard and provided forward of the center of the latter with a notch and at opposite sides of the center with deeper V-shaped notches, and a catch secured to one of said brackets and provided with a tooth overlying the said part and engaging either of the notches thereof.
6. A mail bag station crane, comprising a standard, a sleeve arranged to turn and slide thereon, a horizontally bifurcated bracket secured to each end of the sleeve, a pair of bell cranks pivoted in the bifurcation of each bracket, springs bearing at their opposite

ends against the brackets and the bell cranks to hold adjacent arms of the latter together, jaws secured to said last-named arms, a part rigid with the standard and provided forward of the center of the latter with a 65 notch and at opposite sides of the center with deeper V-shaped notches, a catch secured to one of said brackets and provided with a tooth overlying the said part and engaging either of the notches thereof, cushions fitting on the said jaws, and a collar secured to the standard to limit downward movement of the rotatable and slid able sleeve and the parts carried thereby.

7. The combination with a standard, a head surmounting the standard and provided in its front side with a shallow notch and at opposite sides of its center with deep notches, a rotatable and slid able bag carrying frame mounted on the standard, embodying spring closed jaws, a catch bearing a fixed relation to said frame and provided with a tooth overlying said head and adapted to engage either of said notches, a collar mounted on the standard below the said 80 frame, and an elevated platform at the opposite side of the standard from the said shallow notch to underlie the free end of said jaws when the tooth of the catch is in engagement with either of the said deep 85 notches.

8. The combination with a standard, a head surmounting the standard and provided in its front side with a shallow notch and at opposite sides of its center with deep notches, a rotatable and slid able bag carrying frame mounted on the standard embodying spring closed jaws, a catch bearing a fixed relation to said frame and provided with a tooth overlying said head and adapted to engage either of said notches, a collar mounted on the standard below the said frame, an elevated platform at the opposite side of the standard from the shallow notch to underlie the free end of said jaws 95 when the tooth of the catch is in engagement with either of the said deep notches, a bracket secured to the catch, a plate carried by the bracket and overlying said notched head, and a cover secured to the opposite end 100 of the bracket and overlying the outer or free ends of the jaws when the same are closed.

In testimony whereof I affix my signature, in the presence of two witnesses.

ALBERT HUPP.
